LOCK MECHANISM

William S. Diehl, Shillington, Pa., assignor to
Reading Hardware Corporation, Reading, Pa.,
a Corporation

Application December 19, 1931. Serial No. 582,133

12 Claims. (Cl. 70—91)

This invention relates to improvements in lock mechanisms.

The primary object of this invention is the provision of an improved cylinder type of lock which is adaptable for use upon ballot boxes and in connection with voting machines, although not limited in use thereto; the improved lock embodying a simple and sturdy arrangement of well guarded locking parts which will enable the lock 10 to be key controlled.

A further object of the invention is the provision of an improved cylinder lock having an improved handle unit associated therewith.

Other objects and advantages of this invention 15 will be apparent during the course of the following detailed description.

In the accompanying drawings, forming a part of this specification, and wherein similar reference characters designate corresponding parts 20 throughout the several views,

Figure 1 is a front view of the improved lock, showing the same in locked position, that is, with the bolts and locking arms thereof in locking position.

Figure 2 is a cross sectional view taken axially in a vertical plane through the improved lock mechanism, showing a key inserted in position just prior to turning for an unlocking operation.

Figures 3, 4 and 5 are transverse sectional views 30 taken substantially on their respective lines in Figure 2 of the drawings.

Figure 6 is a view similar to Figure 1, but with the key inserted in the lock and the lock plunger and cylinder casing in position with the bolts 35 thrown to unlocking position.

Figure 7 is a rear view of the improved lock with the bolt means which is controlled thereby removed.

Figure 8 is a cross sectional view similar to Figure 2, but with the rotatable locking plug turned for retraction of a locking plunger from a closure attached keeper.

Figure 9 is an end view of a locking plug showing the key slot and eccentric cam thereon.

In the drawings, wherein for the purpose of illustration is shown only a preferred embodiment of the invention, the letter A may generally designate the improved lock which is adapted to be used upon a closure or other support B for controlling access to a compartment, such as in a ballot box or voting machine. While the support B is preferably a door or other closure, yet it may be a wall of a container and the bolt means may cooperate with a closure in contradistinction 55 to usual practice.

The improved lock A preferably includes a rotatable cylinder lock casing C having operatively associated therewith a rotatable plug D. Tumbler mechanism E is associated with the casing C and plug D, controlled as to position by 60 means of a key F which is insertable into a key slot in the plug D, to permit relative rotation of the said plug D in the cylinder casing C. In associated relation with the cylinder C is a removable member G of cap-like formation, which 65 acts as a hand hold to facilitate turning of the cylinder casing C; the parts C and G being fixedly connected together at all times. The closure or other support B is provided with a sleeve-like keeper or hub H, in which the rotatable portions 70 of the lock mechanism are supported, for rotation. A locking plunger or member K is controlled by the plug D for selectively keying or locking the cylinder C with the keeper H. The cylinder C has associated therewith in an im- 75 proved manner, bolt mechanism L, which may be of any approved nature, and which is used to bolt the closure of a container in place.

The lock casing C, as above mentioned, is of cylindrical construction. At its inner end it is 80 axially provided with a reduced polygonal shaped projection 30, integral with the body of the casing C, and a further reduced axially extending externally screw threaded shank 31. The bolt mechanism L is adapted to be received on the 85 portion 30. It consists of a body 32 having a squared opening therein which will snugly receive the extension 30 in order to fixedly key the body 32 for rotation with the cylinder C. The body 32 is of the same thickness as the extension 90 30 and abuts against a shoulder 34 at the inner end of the body of the cylinder lock casing C. A washer 35 is slipped over the shank 31 and a nut 36 screwed on the latter for clamping the washer against the body 32 of the bolt mechanism in 95 order to prevent the latter from falling off the casing C.

The body portion 32 of the bolt mechanism L may be of any approved nature. It is preferably of the three-way bolting type, such as used upon 100 locker doors, safe doors, and ballot and voting machine boxes. To that end it is preferably provided with a radially extending locking lug 40, and at 90° thereto, and in relative diametrically opposed relation, there are also provided 105 radial extensions 41 and 42 to which locking bars or arms 44 and 45 are respectively pivoted. These locking bars or arms 44 and 45 are of the well-known type and their keeper control need not be further described.

The closure or other support B which rotatably supports the lock mechanism is provided on the inner surface thereof with the hub H which serves as a rotatable support for the cylinder lock, and also as a keeper for the locking plunger K. This member H includes a cylindrical body portion 46 which at one end thereof is provided with preferably four radially extending lugs 47 apertured at 48, as shown in Figure 7, and adapted to receive rivets 49 for bolting the same upon the inside of the closure or other support B. The latter is provided with an opening 49^a therein, and the hub or member H is provided with an annular lip extension 50 which projects into the support opening 49^a, as shown in Figures 2 and 8 of the drawings. The hub or sleeve member 46 is provided with an outwardly facing socket 51 which terminates in an annular shoulder 52 arranged in a plane normal to the axis of the lock, and the rear portion of the keeper or member H is provided with a passageway 53 therethrough, of the same diameter as the cylinder lock casing C, and adapted to rotatably receive the same directly therein.

25 The cylinder lock casing C is, of course, of cylindrical formation for rotation within the support attached hub or sleeve member H. Opening on its outer end it is provided with the plug socket 60 therein, which terminates in a dead end 61.

30 The locking plug D is rotatably received in this socket 60; the said locking plug D including a body portion 63 of substantially uniform diameter, which at the outer end is provided with an annular flange head 64. At its inner end, short 35 of the dead end 61 the plug D is provided with a rigid eccentric cam extension 66. The locking plunger or member K is slidably supported in a passageway 68 provided radially in the lock casing C therefor; the passageway 68 intersecting the rear end of the plug socket 60 and opening radially at one point on the casing. The hub member or lock support sleeve H is provided with a keeper opening 71 adapted to receive the end of the locking plunger K. The latter is provided with a lateral opening 74 which receives the eccentric cam extension 66 therein. Thus, as the plug D is rotated the plunger K will be moved into and out of the keeper opening or socket 71, that is, when the parts are properly positioned for such action.

40 The movement of the plug D is limited to a turn of approximately 90° in order to enable the locking plunger K to be thrown into full locking and full retracted relation with respect to its keeper socket 71. This angular movement of the plug D in the cylinder C is controlled by means of a set screw 80, shown in Figure 5, which is detachably carried by the casing C, and which has an inner reduced end projecting into a slot 81 which is circumferentially recessed into the plug D, near the inner end of the latter, for a distance of about 90° or more.

45 The tumbler mechanism E is of the usual type, and need not be further described except to say that the springs thereof are held in position by means of the cap G, in lieu of the usual metal slide which is additionally provided therefor. This cap G includes a body portion 90 having a socket 91 therein which receives the outer end of the cylinder casing C. The inner end 92 of the cap body 90 is reduced, and fits into the enlarged portion 51 of the passageway through the hub or lock supporting member H; the annular shoulder 95 at the juncture of the reduced portion 92 with the body 90 of the cap G abutting

and overlapping in a secreting relation the outer edge of the hub H which is seated in the opening 49^a, and also overlapping the marginal portion of the closure or other support B which surrounds the opening 49^a, in order to secrete the joint. 80

50 The cap or member G is rigidly connected with the casing C, although in a removable manner, by means of countersunk set screws 98, shown in Figure 4 of the drawings, which are mounted in openings in a reduced inner end 92 of the member G, and thus secreted in the hub H when the lock is in position. The cap G is provided with an outer annular wall 100 which covers the outer end surface of the cylinder lock casing C, and which has an opening therein snugly and rotatably receiving the head portion 64 of the plug D, as shown in Figure 8. It will be noted from Figures 2 and 8 of the drawings that the cap G receives the entire portion of the casing C therein upon which the tumbler mechanism is mounted, so that the springs of the tumbler mechanism are retained by this cap. 95

55 The relation in which the cylinder lock may be turned in the sleeve lock support H is limited for a proper throw control of the bolt mechanism L. This is accomplished by providing a screw 105, shown in Figure 3 of the drawings, which is detachably mounted upon the member H, at the inner side of the closure or wall D, and which has a reduced end 106 projecting into a slot 107. The latter is recessed for a short distance circumferentially about the outer surface of the cylinder lock casing C, in order that the casing may be thrown for a turn which will enable the bolt mechanism L to be drawn into or out of position with respect to the keepers (not shown) provided therefor.

60 From the foregoing description of this invention it is believed the operation and control of the locking mechanism will be apparent. In order to unlock the bolt mechanism L for access to the container upon which the lock mechanism is used, the key F is inserted into the position shown in Figure 2, for properly positioning the tumblers of the tumbler mechanism. Upon turning of the key F to the right, for a short angular turn, the plug D will be rotated, and through its cam connection with the plunger K the latter will be withdrawn from the keeper socket 71, to the position shown in Figure 8 of the drawings. The cap G is provided with diametrically opposed handle extensions 110 which may then be grasped by the operator and the entire cylinder lock casing, together with the cap G and key mechanism 130 thereon, may be rotated for throwing the bolt mechanism L to an unlocked position. It will be noted that so long as the plunger K is in the unlocked position shown in Figure 8, the key F can- 125 not be withdrawn. 135

65 Various changes in the shape, size, and arrangement of parts may be made to the form of invention herein shown and described, without departing from the spirit of the invention or the scope of the claims. 140

70 I claim:

75 1. In a cylinder lock the combination of a cylinder casing, a rotatable plug therein having a key slot, said cylinder casing and plug having a tumbler receiving passageways opening upon the outer periphery of the cylinder casing, a bolt actuating cam carried by the plug, tumbler mechanism in said passageways of the cylinder casing and plug for controlling rotation of the plug with- 145 in the cylinder casing, and a cap rigidly and re- 150

- movably affixed upon the outer end of the cylinder casing with the latter in a secreted relation therein, said cap overlying and holding the tumbler mechanism in position in the said passage-
5 ways and having a front wall secreting the cylinder casing and provided with an opening there-
in exposing the outer end of the plug. 80
2. In a lock mechanism the combination of a support upon which the lock is to be mounted
10 and having a lock receiving opening therein, a sleeve-like keeper member affixed upon the inner side of the support and having a passageway therethrough aligning with the opening of said support, said sleeve-like keeper having at the inner side of said support a transverse socket opening into said passageway of the sleeve, a cylinder casing rotatably bearing in said passageway of the sleeve-like member, a plug rotatable in the cylinder casing, a plunger having a cam connec-
15 tion with the plug and actuatable upon rotation of the plug into and out of projecting relation with respect to the socket of the sleeve-like member, a removable handle cap on the outer end of the cylinder member at the outer side of the support
20 and having a reduced annular portion bearing in the sleeve-like keeper member and overlapping the jointed connection surrounding the opening of said support, said cap having a front wall with an opening therein in which the outer end of the
25 plug is exposed, said plug having a key slot there-
in, and tumbler mechanism associated with the plug and the cylinder casing and having springs actuatable against the cap and maintained in position thereby. 105
3. In a lock mechanism the combination of a support upon which the lock is to be mounted and having a lock receiving opening therein, a sleeve-like keeper member affixed upon the inner side of the support and having a passageway therethrough aligning with the opening of said support, said sleeve-like keeper having at the inner side of said support a transverse socket opening into said passageway of the sleeve, a cylinder casing rotatably bearing in said passageway of the sleeve-like member, a plug rotatable in the cylinder casing, a plunger having a cam connec-
40 tion with the plug and actuatable upon rotation of the plug into and out of projecting relation with respect to the socket of the sleeve-like member,
45 a removable handle cap on the outer end of the cylinder member at the outer side of the support and having a reduced annular portion bearing in the sleeve-like keeper member and overlapping the jointed connection surrounding said opening in the support, said cap having a front wall with an opening therein in which the outer end of the plug is exposed, said plug having a key slot there-
50 in, tumbler mechanism associated with the plug and the cylinder casing and having springs actuatable against the cap and maintained in position thereby, and bolt means connected with the cylinder casing at the inner side of said support and actuatable upon rotation of the cylinder casing into locking and unlocking positions. 110
4. In a lock mechanism the combination of a support upon which a lock is to be mounted and having a lock receiving opening therein, an elongated sleeve fixed upon the inner side of the support and having a passageway therethrough aligning with the opening in the support, said sleeve having a transverse socket opening into its passageway, a cylinder rotatably bearing in said sleeve and extending through the opening to the outer side of the support, a plug rotatable in the cylinder, a plunger having a cam connection with
55 the plug and actuatable upon rotation of the plug into and out of locking relation with the socket of the sleeve, key actuated tumbler mechanism for controlling rotation of the plug within the cylinder, and bolt means having an operating connection with the cylinder at the inner side of said support and actuatable upon rotation of the cylinder into locking and unlocking positions. 85
5. In a lock mechanism the combination of a support upon which a lock is to be mounted and having a lock receiving opening therein, an escutcheon or rose bearing fixed upon the inner side of the support and having a passageway therethrough aligning with the opening in the support, said escutcheon having a socket opening transversely into its passageway, a cylinder rotatably bearing in said escutcheon and extending through the opening to the outer side of the support, a plug rotatable in the cylinder, a plunger having a cam connection with the plug and actuatable upon rotation of the plug into and out of locking relation with the socket of the escutcheon, key actuated tumbler mechanism for controlling rotation of the plug within the cylinder, bolt means having an operating connection with the cylinder at the inner side of said support and actuatable upon rotation of the cylinder into locking and unlocking positions, and a removable hand actuating cap upon the cylinder at the outer side of the support surrounding and secreting the jointed connection where the cylinder extends through the support and affixed to the cylinder for rotation therewith, the cap having an opening at the front thereof to expose the key slotted end of the plug. 90
6. In a cylinder lock mechanism the combination of a keeper adapted to be attached fixedly to a wall or closure and having a passageway therethrough and a lateral socket opening into the passageway, a cylinder rotatably bearing at its inner end in the keeper passageway, a key actuated pin tumbler controlled plug rotatable in the cylinder, a plunger transversely slidably in the cylinder having a cam connection with the plug whereby upon rotation of the plug the plunger may be locked in the said socket of the keeper, means on the inner end of the cylinder for controlling a bolt mechanism, and a removable cap on the outer end of the cylinder having means for affixing the same to the cylinder at a location 100 within the passageway of the keeper. 115
7. In a cylinder lock mechanism the combination of a keeper adapted to be attached fixedly to a wall or closure and having a passageway therethrough and a lateral socket opening into the passageway, a cylinder rotatably bearing at its inner end in the keeper passageway, a key actuated pin tumbler controlled plug rotatable in the cylinder, a plunger transversely slidable in the cylinder having a cam connection with the plug whereby upon rotation of the plug the plunger may be locked in the said socket of the keeper, means on the inner end of the cylinder for controlling a bolt mechanism, and a removable cap on the outer end of the cylinder having means for affixing the same to the cylinder in socketed relation within the passageway of the keeper, the said cap having a front wall overlying the front of the cylinder with an opening therein exposing the key slot end of the plug. 120
8. In a lock mechanism the combination of a support upon which the lock is to be mounted having a lock receiving opening therein, a sleeve-like keeper member affixed upon the inner side of the support and having a passageway there-
125 130 135 140 145 150

through aligning with the opening of the support, and provided with a lateral socket opening into the passageway thereof, a cylinder rotatably bearing at its inner end in the passageway of the keeper, a key actuated pin tumbler controlled plug rotatable in the cylinder, a plunger having a cam connection with the plug and actuatable upon rotation of the plug into and out of projecting relation with the socket of the keeper, a removable cap over the outer end of the cylinder having a reduced end extending through the opening of the support into socketed relation in the keeper passageway, means fixedly securing said reduced end of the cap to the cylinder, the outer end of the cap overlying and secreting the edge of the opening in the support.

9. In a lock mechanism the combination of a support upon which the lock is to be mounted having a lock receiving opening therein, a sleeve-like keeper member affixed upon the inner side of the support and having a passageway therethrough aligning with the opening of the support, and provided with a lateral socket opening into the passageway thereof, a cylinder rotatably bearing at its inner end in the passageway of the keeper, a key actuated pin tumbler controlled plug rotatable in the cylinder, a plunger having a cam connection with the plug and actuatable upon rotation of the plug into and out of projecting relation with the socket of the keeper, a removable cap over the outer end of the cylinder having a reduced end extending through the opening of the support into socketed relation in the keeper passageway, means fixedly securing said reduced end of the cap to the cylinder, the outer end of the cap overlying and secreting the edge of the opening in the support, said cap having a laterally extending handle thereon to permit the turning of the same and the cylinder.

10. In a lock mechanism the combination of a sleeve-like keeper having means to attach the same to the inside of a support which is to be locked, said keeper having a keeper socket therein, a cylinder rotatable in the keeper, a plug rotatable in the cylinder, key controlled tumbler mechanism operatively associated with the cylinder and plug, a laterally movable locking plunger

actuated by the plug in retracting and projecting relation with the keeper socket, bolt mechanism having an operating connection with the inner end of the cylinder beyond the keeper and actuated by rotation of the cylinder to locked and unlocked positions, said cylinder having a slot therein about part of the circumference thereof, and a set screw in the keeper having an end extending into said slot to limit the amplitude of rotation of the cylinder when the plunger is retracted from the keeper socket to permit cylinder rotation.

11. In a lock mechanism the combination of a sleeve-like keeper having a passageway therethrough and provided with a transverse socket opening into the passageway, means for attaching said keeper to a support, a cylinder casing rotatably bearing in said passageway of the sleeve, a plug rotatable in the cylinder casing having a key slot, a plunger having a cam connection with the plug and actuatable upon rotation of the plug into and out of locking relation with the socket of the sleeve-like keeper member, a cap on the outer end of the cylinder casing in complementary relation with the keeper sleeve, secreting the front end of the cylinder casing therein and having a front wall covering the front face of the cylinder casing, said front wall having an opening therein exposing the key slotted end of the plug, and tumbler mechanism associated with the plug and cylinder casing.

12. In a lock mechanism the combination of a support having an opening therein, a hand turning cap having a front wall with an opening therein and having an internal socket opening rearwardly, said cap having a reduced annular rear portion rotatably bearing in the opening of the supporting wall and at the juncture of the same the cap having an annular shoulder abutting the front face of the supporting wall to secrete the jointed connection of the cap with the wall, a cylinder casing in the socket of the cap and keyed thereto, a key slotted plug rotatable in the cylinder casing having the key slot exposed through the opening in the front wall of the cap, and bolt means having a cam connection with said plug.
